(57) **CLAIM**

The ornamental design for a sport earphone protective box, as shown and described.

DESCRIPTION

FIG. 1 is a perspective view of a sport earphone protective box showing my design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the sport earphone protective box in which the design is embodied that form no part of the claimed design.
